RAZOR BLADE RECEPTACLE

Irving S. Bodkin, New York, N. Y., assignor to
 Conrad Razor Blade Co., Inc., New York, N. Y.,
 a corporation of New York

Application April 28, 1939, Serial No. 270,541

3 Claims. (Cl. 206—16)

The present invention relates generally to razor blade receptacles and more particularly to an improved inexpensive construction which may be readily made from a molded material such as a phenolic condensation product having a compartment for holding packages of new blades and a compartment for housing and concealing used blades.

The disposal of safety razor blades presents a real and constant problem in almost every home as well as in hotels, Pullman trains and similar places. If left on shelves, the blades rust and become unsightly. Furthermore, children are likely to gain access to them and injure themselves. If thrown in waste paper baskets, there is danger of the person removing the waste being cut by the blades. Even if the blades are thrown outdoors, there is still the likelihood of children finding them and sustaining injuries. The present device is a simple inexpensive receptacle for holding used blades and also for holding packages of new blades. The used blades are concealed and the new blades are in endwise position to expose a substantial part of the package and thereby serve as a display receptacle, if desired. A further advantage of the invention is the construction of the receptacle whereby the entire box with the exception of a concealed section can be made of "Bakelite" in a single molding operation. The concealed additional section may be of metal colored to simulate "Bakelite" and thereby give the appearance of a unitary vault-like structure molded entirely of "Bakelite." The construction also lends itself to a simple molding operation and thereby permits of mass production and corresponding low costs.

An object of the present invention is to provide an improved razor blade receptacle.

Another object of the invention is to provide a receptacle for effectively displaying razor blades.

Another object of the invention is to provide an improved type of razor blade receptacle adapted to expose a substantial portion of the razor blades contained therein.

Another object of the invention is to provide a razor blade receptacle having a vault-like compartment for receiving and concealing used razor blades in combination with a display compartment for new blades.

A further object of the invention is to provide a receptacle for both new and used blades which may be molded from "Bakelite" in a single molding operation with the exception of a single section which may be a concealed metal insert.

Other and further objects of the invention

will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming part of the specification, wherein

Fig. 1 is a perspective view of a preferred embodiment of the invention with one corner broken away to show the position of the used blades;

Fig. 2 is a view taken along the line 2—2 of Fig. 1; and

Fig. 3 is a view taken along the line 3—3 of Fig. 2 showing the metal insert about to be inserted.

Referring again to the drawing, there is shown a razor blade receptacle 1 having a compartment 2 at one side of the device adapted to retain new blades in exposed position, some of which are shown in dotted lines therein. At the other side of the receptacle 1 is a closed vault-like compartment 4 for receiving used blades.

The normally open compartment 2 for holding new blades preferably comprises a bottom or base portion 5 adapted to support razor blades, with a strengthening rib 6 extending thereacross, wall portions 7 and 8 extending upwardly from the sides of the base 5 and wall portions 9 extending upwardly from the ends of the base 5. The upper portions of the end walls 9 are preferably cut away as at 10 to expose to view substantial portions of new blades and their wrappers, together with any advertising matter thereon (Fig. 1). The base portion 5, together with the wall portions 7, 8 and 9, forms a compartment with a normally open or exposed upper end for facilitating insertion, and removal of blades therein.

While blades may be inserted in any position within the open compartment, they are preferably stood up on end therein as shown in dotted lines in Fig. 1. From this position a blade may be more easily removed without disturbing other blades. A partition 11 preferably extends across the open compartment adjacent the lower part thereof and connects with the side walls 7 and 8. This partition assists in holding blades upright within the compartment, particularly when the compartment is only about half filled with blades and prevents them from resting horizontally in the compartment. The partition 11 also

strengthens the compartment by forming, in effect, buttresses for the walls 7 and 8.

The normally closed or vault-like compartment for holding used blades utilizes the side wall 8 of the open compartment 2 for one side wall thereof, the end walls 9 of the open compartment are extended to form the end walls of the second compartment, and an additional side-wall portion 13 connects the end wall portions 9 to form a compartment of sufficient size to contain razor blades 14 in horizontal position therein (Figs. 1 and 2).

A cover portion 15 extends over the top of the second compartment 4, and is preferably carried by the side walls 8 and 13 thereof. This top or cover portion 15 is preferably slightly shorter than the length of the closed compartment 4 so as to assist in forming a gap or slit 16 with the end walls 9, and the end walls 9 are themselves preferably cut away or recessed slightly adjacent their upper ends for substantially the width of the compartment. This construction provides an aperture at the junction of the end walls 9 with the cover 15, which is adapted to permit passage of razor blades therethrough into the compartment (shown in dotted lines in Fig. 2). Razor blades may thus be inserted through the apertures so as to lie in substantially horizontal position at the lower part of the compartment 4.

The bottom of the compartment 4 differs from the molded bottom 5 of the new blade compartment in that a metal insert 17 is utilized. By utilizing the metal insert it is possible to mold the rest of the receptacle in a single molding operation in a multiple mold press. Thus a number 30 of them can be molded in a single heat. The assembly operations, which are generally expensive because of the labor required, consist in the single insertion of the metal bottom 17. Furthermore, the metal insert may be coated black to 35 simulate "Bakelite" and the entire receptacle appears to be a unitary molded structure. This increases the attractiveness of the receptacle, which is an important element in household articles. The insert may be coated other than black.

Preferably the bottom member 17 is carried within a recessed portion 18 formed by grooves or channels 19 at the lower parts of the side and end walls of the compartment. Projections 20 extend inwardly from the channels to maintain the bottom member 17 in its normal closed position out of contact with the shelf or other support upon which the device rests. Spacing the bottom member 17 above the extreme lower part of the receptacle base decreases the possibility 50 of its contacting any water and consequent rusting.

The size of the receptacle is such that the blades normally discarded during a year or more may be contained in the used blade compartment. The low cost of the article permits it to be thrown away when filled. However, the bottom member 17 may be easily lifted over the retaining projections 20, by means of a knife or other similar instrument, and the blades removed. After emptying, the bottom member 17 may be easily pressed or snapped back over the projections 20 into closed position and the inherent resiliency of the material of which it is formed will hold it securely in position. The used blades 60 may also be removed by inverting the receptacle and shaking the blades out through the recesses 16.

It will be seen that the present invention provides an inexpensive razor blade receptacle 78 in

adapted to maintain new blades in view at all times and adapted to provide a safe means for disposing of used blades. A used blade may be deposited within the device and a new blade taken therefrom to replace it; both the new blades and the depository for used blades are immediately available at all times. When a sufficient number of used blades have accumulated, the receptacle may be thrown away or the bottom member of the used blade compartment may be removed and all of the blades therein disposed of at the same time. A single razor blade receptacle may thus be used for an indefinite period of time and the manufacturer or distributor of the receptacle can afford to supply a device which is more satisfactory and which presents a better appearance. Dirt-catching joints or crevices and parts likely to rust are reduced to a minimum.

20 As various changes may be made in the form, construction and arrangement of the parts herein without departing from the spirit and scope of the invention and without sacrificing any of its advantages, it is to be understood that all 25 matter herein is to be interpreted as illustrative and not in a limiting sense.

Having thus described my invention, I claim:

1. A receptacle for safety razor blades comprising, in combination, a unitary molded part having a pair of compartments separated by a wall common to each, the top of one compartment being open and the bottom of the other compartment being open to permit it to be made as a unitary structure, the open bottom compartment having its transverse and longitudinal dimensions at least as great as the longitudinal and transverse dimensions of a conventional razor blade to be placed in the compartment, the open bottom compartment having a longitudinal dimension substantially equal to that of the open top compartment, means projecting into said open bottom portion from the sides of the open compartment, a dish-shaped insert member adapted to be snapped into the bottom of said open bottom compartment so that the edges thereof rest against said projecting means to retain the insert in position and to form a vault-like compartment therefrom, said vault-like compartment having a slot therein along a top horizontal corner thereof to facilitate molding and for the insertion and removal of used razor blades.

2. A receptacle for safety razor blades comprising, in combination, a unitary molded part having a pair of compartments separated by a wall common to each, the top of one compartment being open and the bottom of the other compartment being open to permit it to be made as a unitary structure, the open bottom compartment having its transverse and longitudinal dimensions at least as great as the longitudinal and transverse dimensions of a conventional razor blade to be placed in the compartment, the open bottom compartment having a longitudinal dimension substantially equal to that of the open top compartment, the sides of the open bottom portion having means for engaging and holding an insert, an insert member substantially the size of the opening adapted to be secured in the opening of said open bottom compartment so that the insert closes said open bottom compartment to form a vault-like compartment therefrom, said vault-like compartment having a slot therealong a top horizontal corner thereof to facilitate molding and for the insertion and removal of used razor blades.

tate molding and for the insertion and removal of used razor blades.

3. A receptacle for safety razor blades comprising, in combination, a unitary molded part having a pair of compartments separated by a wall common to each, the top of one compartment being open and the bottom of the other compartment being open to permit it to be made as a unitary structure, the open bottom compartment having its transverse and longitudinal dimensions at least as great as the longitudinal and transverse dimensions of a conventional razor blade to be placed in the compartment, the open bottom compartment having a longitudinal dimension substantially equal to that of 15

the open top compartment and having a partition extending across the compartment to retain razor blades in endwise position therein, the sides of the open bottom portion having means for engaging and holding an insert, an insert member substantially the size of the opening adapted to be secured in the opening of said open bottom compartment so that the insert closes said open bottom to form a vault-like compartment 10 therefrom, said vault-like compartment having a slot therein along a top horizontal corner thereof to facilitate molding and for the insertion and removal of used razor blades.

IRVING S. BODKIN.
